PLASTIC DOORKNOB CONSTRUCTION

Morris Falk, Leominster, Mass., assignor to Independent Lock Company, Fitchburg, Mass., a corporation of Massachusetts

Application October 27, 1938, Serial No. 237,179

18 Claims. (Cl. 292—347)

This invention relates to doorknobs, and more particularly to doorknobs of ornamental character.

The general object of my invention is the provision in a doorknob of a simple and inexpensive construction, but one that is at the same time rugged and is susceptible of highly artistic ornamental embodiment.

Modern taste in builder's hardware, and particularly in hardware for the home which frequently requires adherence to a definite color scheme, calls for great variety in color and finish and multicolored finishes are in great demand. Accordingly dealers and manufacturers of such hardware must be prepared to supply any given item in a great many colors and finishes.

Where the article is of one color or finish throughout the problem of manufacturing and stocking it in a number of colors and finishes is serious enough, as it prevents production in large runs, thereby increasing the cost, and the investment involved in stocking the article in various finishes is enormously increased.

The problem is further complicated where the article is multicolored, as is frequently the case in hardware of modern design in which metallic fittings are frequently used in combination with parts of other materials, such as the colorful products of the manufacturers of synthetic resins. The consumer may call for a particular color in one part and another color in another part, and the variety of combinations that may be called for is very great.

Among the objects of my invention is therefore further the provision of a doorknob whereby it is constituted of interfitting parts that may be separately finished and enable the inexpensive production of multi-colored finishes, the parts of which are interchangeable with other parts, and the parts of which are readily assembled and disassembled.

As a consequence a dealer need only stock the various parts in a variety of finishes and colors, and from this stock he may quickly assemble the desired combination called for. As an alternative, of course, he may stock a limited number of assemblies and additional parts by the use of which one of the assemblies may be converted to the exact color and finish called for. The manufacturer on the other hand may make only the individual parts, or, if he desires to furnish complete assemblies, may restrict these to a limited number of colors and finishes.

To attain these objects and such further objects as may appear herein or be hereinafter

pointed out, I make reference to the accompanying drawing forming a part hereof, in which:

Figure 1 is a front elevational view of my improved doorknob;

Figure 2 is an enlarged sectional view thereof;

Figure 3 is an exploded view showing the parts constituting my improved doorknob arranged substantially in the order in which they are assembled, and each part being shown in perspective;

Figure 4 is a plan view on an enlarged scale of the doorknob body portion;

Figure 5 is a bottom plan view of the interlocking member of the doorknob;

Referring to the drawing in detail, there is therein designated a body portion 10 of a doorknob, a shank portion 12, a washer 14, adapted to be positioned intermediate the body portion and the shank, and a member 16 for interlocking the body portion 10 and the shank portion 12. 10 15 20 25 My improved doorknob further includes a top piece or cap 18 adapted to seat on the body portion 10 and to close the opening therein, and means to hold the member 16 in its interlocking position, such means being shown by way of example, as a screw 20 and a lock washer 22.

The body portion 10, the shank 12 and the washer 14 are so contoured and dimensioned in relation to the locking member 16 that when the latter is drawn toward the shank, the body portion will be pressed against the washer 14, and all the parts will be firmly interlocked into a rigid unit.

The body portion 10 is shown as of a character that adapts itself readily for manufacture from a variety of materials, and in particular from one of the many modern synthetic plastics such as phenol formaldehyde condensation products, polymerized vinyl compounds and plasticized cellulosic compounds such as cellulose acetate, all of which may be made by a molding, die casting or injection casting method. These materials besides being suitable from the standpoint of ease of manufacture, fill the requirements of beauty of appearance and finish and variety of coloring.

The body portion 10 is shown as hollow, and is provided with grooves 24 running inwardly along the inner walls thereof, and having transverse 50 ribs 26 spaced from the base of the grooves, for a purpose that will presently appear. The grooves are formed in an annular section 25 which terminates short of the mouth of the opening to provide a shoulder 25A and a broader shoulder 55

25B which serves to support the flange 19 of the top piece or cap 18.

The bottom 28 of the body portion has a centrally, positioned opening 30 therein, which opening is non-circular, so that when the projecting portion 32 of the locking member 16, the contour of which is complementary to that of the opening 30, is inserted therein, these parts will be interlocked against relative turning. For this purpose, the portion 32 is shown as in the shape of a cylinder, flattened on opposed sides, as at 33 and is further provided with means for taking up play between these parts, as will appear hereinafter.

15 As clearly appears from Figs. 2 and 4, the member 16 is provided with a pair of recesses 34 formed in its projecting portion 32, these recesses being of a shape to receive therewithin the spaced upstanding lug portions 36 of the shank 12. Between the recesses 34 of the member 16 is a second projecting portion or boss 38 adapted to fit into the space between the lugs or portions 36 of the shank. As can be seen from Fig. 2, the flange portions 39 of the member 16 overlie the bottom 20 25 28 of the body portion 10, and all of the parts just described are so contoured that they will interfit so that relative rotation between them is prevented. They are further so proportioned that the screw 20 will draw them together in an axial direction until they are firmly interlocked.

When the lugs 36 are interfitted with the member 16, it will be observed that the external configuration of the combined portions 36 and 38 is cylindrical and of such size that it will be accommodated within the opening 40 of the washer 14, the rim portions of which are adapted to seat within the recess 58 of the body portion. In order to allow for variations between the sizes of the opening 30 and the projection 32 and still 40 secure firm interfitting, teeth 44 may be provided at the base portions of the flat walls 33 of the projection 32. These teeth may be so contoured and the materials of parts 16 and 10 so selected that the teeth will bite into the softer materials of the adjacent walls of the body portion 10 and thereby firmly seat themselves and the member 16 in place. Alternatively, of course, the teeth might be made of the softer material; in either case a firm seating is secured. For 45 securing this effect, the teeth are shown as provided with sharp edges tapering downwardly, and when the member 16 is drawn against the shank by the screw 20, the two rows of teeth 44 will wedge into the opening 30 and the parts will be firmly interlocked.

When the body portion 10, and the shank 12, the interlocking member 16 and the washer 14 are in assembled relation, it will be observed that they mutually firmly support each other in the proper relation. Permanence in such assembled relation is secured by inserting the screw 20 through the opening 46 of the flange 47 at the top of the threaded bore 48 of the shank, and into the threaded opening 50 in the member 16.

60 65 The lock washer 22 may be placed under the head of the screw 20 and will then perform its customary function of resisting movement of the screw, such as would loosen it.

The ease with which the assembly of the parts 70 may be effected will be apparent. The washer 14 is first placed in the shank 12, the body portion 10 is seated in the washer, and the member 16 is properly positioned by inserting it through the open end of the body portion 10 and seating 75 it in place in the opening 30 and on the shank

12. The parts are readily held in place while the screw 20 and lock washer 22 are applied to draw the parts together.

Adjacent the exterior portion of the knob 10 I form an annular flange 58 into which the rim 5 of the washer 14 may be seated.

The washer is preferably dished to add resiliency and where it is seated over the lugs 36 abuts the shoulder 37 formed on the shank 12 and extending to either side of the upstanding 10 lugs 36. Interposing the washer 14 between the knob 10 and the shoulder 37 provides an exceedingly desirable construction especially where the washer 14 is dished in that by this construction the bottom 28 of the knob where this 15 is made of rather fragile plastic material is resiliently engaged between the interlocking member 16 and the shoulder 37. This resiliency is in addition to that which may be offered by the spring washer 22. Additionally also, by separately forming the shank 12 and the washer 14 great economy is effected by reason of the fact that the stock of material which is employed for making the shank 12 is of minimum dimension.

20 Additionally, also, apart from the resilient connection obtained in interposing the washer 14 between the knob 10 and the shoulder 37 of the shank 12 quick interchange of parts may be effected so that a definite color combination may be obtained as between the ornamental finish 30 which may be given to the washer 14 and the doorknob 10. Thus, as will hereinafter appear, if the chromium plating, nickel plating, gun metal or colored enamel finish is intended to be contrasted with the color tone of the doorknob 35 10 whether it be made of metal or plastic, the interposing of the washer 14 and its manner of mounting makes possible a quick and ready interchange of this part with the desired color tone or with any other predetermined color tone depending upon the color combination to be effected 40 by the assembly.

To complete the doorknob and to give it its final ornamental touch the top piece 18 is added to the assembly just described. It is shown as 45 provided with prongs 52 adapted to enter the grooves 24 of the body portion 10. The prongs 52 are made sufficiently resilient and they have transverse grooves 54 in the outer surfaces of their end portions, so that when they are inserted into the grooves 24 of the body portion 10 50 they will snap into place, with the ribs 26 of the body portion seated in the grooves 54 of prongs, as shown in Fig. 2.

55 Disassembly of the complete knob for the purpose of interchanging parts or for other purposes is readily effected by first removing the screw 20, which will enable separation of the shank 12 (and the washer 14 if desired) and then pushing the member 16 inwardly and against the top 60 piece thereby forcing it out of its seat in the body portion.

For the sake of completeness attention may be called to the threaded bore 48, adapted to fit on a threaded spindle and the threaded opening 65 56 adapted to receive a screw to lock the knob to the spindle, these being conventional features.

Attention will now be directed to the simplicity and economy of design enabling my improved doorknob to be produced at low cost. The use 70 of metals or of synthetic plastics of different color-tones or ornamental finish for the body portion 10 has already been mentioned. The member 16 is conveniently and cheaply made of metal by the die casting process. The spindle 75

or shank 12 is a turning that is relatively low in cost because of the small diameter of the stock that may be used. The top piece 18 and the washer 14 are sheet metal stampings that may be cheaply and easily produced and given various predetermined finishes of ornamental character for effecting various color combinations with the knob portions.

It will therefore be obvious that by the ready interchangeability of the parts of my doorknob and their low cost, great variety in color combinations and finish may be obtained by a dealer or a manufacturer from a stock of parts that are small in quantity and low in cost.

Having thus described and illustrated my invention, what I desire to secure by Letters Patent is:

1. A doorknob comprising a hollow body portion open at the top and having a non-circular opening in its bottom and a shallow recess on its bottom surface, a top piece adapted to close the opening in the top of the body portion, said piece and said body portion being provided with complementary means for yieldably interlocking them, a washer seating in said recess of the body portion, a shank having spaced projections thereon extending through the opening in the washer, a member having portions adapted to seat snugly within the opening in the bottom of said body portion when pressed thereto, said member having recesses therein adapted to receive said projections on the shank, and said member having a projection thereon adapted to extend and to fit into the space between said projections on the shank, and means for drawing said member toward the shank and thereby to snugly interlock said member, said body portion, said washer and said shank.

2. In a doorknob assembly constituted of readily interchangeable parts, a shank arranged to receive a spindle, a resilient washer seating on said shank, a hollow body portion seating on said washer, and means to interlock said body portion and said shank portion against separation and relative rotation independent of said spindle, said means being of such character as to permit its ready removal when desired, and readily removable closure means for said hollow body portion, seating therein independently of said interlocking means.

3. A doorknob construction comprising a relatively heavy metallic shank, a relatively heavy hollow body portion, a dished, resilient sheet metal washer interposed between said body portion and said shank, a relatively heavy member for interlocking said shank and said body portion against separation and relative rotation, and a thin sheet metal closure for said hollow body portion, said closure seating on and interlocking with the said body portion independently of said interlocking means.

4. A doorknob construction comprising a relatively heavy metallic shank arranged to receive a threaded spindle, a relatively heavy hollow body portion made of a molded synthetic plastic material, a dished, resilient sheet metal washer interposed between said body portion and said shank, a relatively heavy member for interlocking said shank and said body portion against separation and relative rotation independent of said spindle, and a thin sheet metal closure for said hollow body portion, said closure seating on and interlocking with the said body portion independently of said interlocking means.

5. A doorknob comprising a shank, a washer

seating on said shank, a body portion adapted to seat on said washer, a member adapted to seat on said shank and having portions thereon interfitting with said body portion, said member serving to interlock said shank and said body portion and prevent separation and relative rotation thereof, and means for holding said member in its interlocking position.

6. A shank for a doorknob, said shank being of tubular conformation and provided at one end thereof with spaced projections having their outer walls contoured so as to lie in a single cylindrical segment, an annular seat surrounding said projections, and a restricted opening between said projections, said opening communicating with the bore of the shank.

7. A shank for a doorknob, said shank being of turned tubular conformation and having a threaded bore, and said shank being provided at one end thereof with spaced projections having their outer walls contoured so as to lie in a single cylindrical segment, an annular seat surrounding said projections, and a restricted opening between said projections, said opening communicating with the bore of the shank.

8. In a doorknob, in combination, a shank of substantially tubular conformation and having a threaded bore provided at one end with spaced projections defining the inner cylindrical wall of an annular seat, and an opening communicating with said bore between said projections, and a washer seating on said annular seat and surrounding said projections, said washer being adapted to be seated in the body portion of a doorknob to engage peripheral portions of said washer.

9. In a doorknob, a bowl-shaped body portion having walls following the general exterior contour of said body having a non-circular opening in its bottom, closure means for the open top of said body portion, and complementary means on said closure and said body portion for removably interlocking them, said complementary means comprising resilient members carried by said closure means and adapted to extend into grooves in the inner walls of said body portion and a shouldered portion on the interior faces of said walled portion to limit said closure means to inward positioning to arrange said closure and knob body to form predetermined contoured portions.

10. In a doorknob, a hollow body portion the walls of which follow generally the exterior contour of said body and provided with grooves in its inner walls having transverse ribs therein and adapted to receive the complementarily contoured portions of a top piece forming a cover for said body portion, said ribs forming an abutment for said top piece to limit the positioning of said cover to the contoured portion.

11. In a doorknob assembly comprising a body portion, a shank and a washer interposed between said body portion and said shank, a member for interlocking said parts comprising a portion adapted to interlock with the body portion of the doorknob and a portion adapted to interlock with the shank, and means adapted to engage said member whereby the said member may be drawn toward the shank so as to hold said body portion, said washer and said shank in interlocking relation.

12. In a doorknob assembly comprising a body portion, a shank and a washer interposed between said body portion and said shank, a mem-

ber for interlocking said parts comprising a portion adapted to interlock with the body portion of the doorknob and a portion adapted to interlock with the shank, and means adapted to engage said member whereby the said member may be drawn toward the shank so as to hold said body portion, said washer and said shank in interlocking relation, and said member being provided with teeth having inclined sides adapted 10 to be forced into the material of the body portion when said member is drawn toward the shank.

13. In a doorknob assembly comprising a body portion of relatively soft material and a shank 15 for receiving a spindle, a member independent of said spindle for interlocking said shank and said body portion to each other and located within the confines of the body portion of said knob, said member being of relatively hard material and being provided with portions adapted 20 to bite into the body portion when pressed thereagainst and thereby to eliminate play between them, and means for causing said member to press against said body portion.

14. A doorknob assembly comprising a body portion of relatively soft material and a shank for receiving a spindle, a member for interlocking said shank and said body portion to each other and located within the confines of the body 30 of said knob, said member being of relatively hard material and being provided with wedge shaped teeth adapted to bite into the body portion when pressed thereagainst and thereby to eliminate play between them, and means for 35 causing said member to press against said body portion.

15. In a doorknob assembly comprising a body portion and a shank adapted to receive a spindle in independently adjustable relationship, a member 40 for interlocking said shank and said body portion, means acting between said shank and said member for drawing said member toward the shank, and causing portions of said member to engage and to press against said body portion, 45 and said engaging portions of said member and of said body portion being respectively of materials one of which is relatively soft and the other of which is relatively hard, whereby when said member engages and is pressed against said body portion the softer material will be deformed by 50 the harder material which will bite thereinto and the parts will be firmly seated together.

16. In a hollow doorknob adapted to be attached to a shank, independently of a spindle connection, a knob body of bowl shape, open at the top, vertical grooves in the inner sides of the walls of said knob body, ribs running transversely across said grooves, and a closure for the open top of said knob body comprising a disc-shaped portion having resilient prongs depending therefrom, said prongs being adapted to enter said grooves in the knob body, and said prongs having transverse 10 grooves therein adapted to receive said ribs in the grooves of said knob body whereby relative rotation of the cover and the body is prevented and removal of the cover from the body is resisted. 15

17. In a doorknob, a knob member having a non-circular opening therethrough, a knob shank having a relatively long body portion abutting at one end one face of the knob member, a relatively short extension having an opening on said 20 abutting end entering the knob member opening, said abutting portion having a spindle receiving bore communicating with the opening of said extension, a securing member operable independently of the spindle for said shank 25 having an enlarged head disposed in said extension and having a portion projecting into said opening, and a retaining member having means at the opposite face of a portion of the knob member non-rotatably engaging said opening 30 and to which said securing member is connected. 35

18. In a doorknob, a knob member having an opening therethrough, portions adjacent thereof being formed to provide non-rotative engagement, a knob shank adapted to receive a spindle having a relatively long body portion abutting at one end one face of the knob member, a relatively short extension having an opening on said abutting end and entering said knob member opening, said abutting portion having a spindle receiving bore communicating with the opening of said extension, securing means adjacent said extension aligned with the opening of said knob member, and a retaining member operative 40 independently of said spindle for said shank having means at the opposite face of a portion of the knob disposed through the opening of said knob member and engaging said securing means, 45 non-rotatably holding said knob member and knob shank. 50

MORRIS FALK.
